(57) **CLAIM**

The ornamental main housing for a medicament injection device, as shown and described.

DESCRIPTION

FIG. 1 is a perspective view of the injection device with the cap portion removed from the distal portion of the main housing and showing a partially extended needle guard viewed from the front and left of and above the injection device;

FIG. 2 is a front end elevation view thereof;

FIG. 3 is a rear end elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a perspective view of the injection device with the cap portion removed from the distal portion of the main housing and showing a retracted needle guard viewed from the front and left of and above the injection device;

FIG. 9 is a front end elevation view thereof;

FIG. 10 is a rear end elevation view thereof;

FIG. 11 is a top plan view thereof;

FIG. 12 is a bottom plan view thereof;

FIG. 13 is a left side elevation view thereof;

FIG. 14 is a right side elevation view thereof;

FIG. 15 is a perspective view of the injection device with the cap portion removed from the distal portion of the main housing and showing a fully extended needle guard viewed from the front and left of and above the injection device;

FIG. 16 is a front end elevation view thereof;

FIG. 17 is a rear end elevation view thereof;

FIG. 18 is a top plan view thereof;

FIG. 19 is a bottom plan view thereof;

FIG. 20 is a left side elevation view thereof; and,

FIG. 21 is a right side elevation view thereof.

The features shown in broken lines depict environmental subject matter only and form no part of the claimed design.

1 Claim, 12 Drawing Sheets
